[57] CLAIM

The ornamental design for a skate and golf shoe upper, as shown and described.

DESCRIPTION

FIG. 1 is a top plan view of the skate and golf shoe upper of the present invention;

FIG. 2 is an outside lateral, full side view of the present invention;

FIG. 3 is a inside, full lateral view thereof;

FIG. 4 is a front view thereof; and,

FIG. 5 is a back view thereof.

The broken line showing of the sole in the Figures is for illustrative purposes only and forms no part of the claimed design.
